VESSEL FOR CONTAINING FLUIDS UNDER PRESSURE

Philip O. Mulkey, Grosse Pointe, Mich.

Application October 23, 1931. Serial No. 570,698

9 Claims. (Cl. 62—1)

This invention relates to improvements in temperature equalizing means in vessels containing gases under pressure during the discharge of said gases from the said vessels, and refers more particularly to equalizing means for use in vessels containing volatile fluids convertible into such gases.

It is well known that liquefied gases under pressure in most cases, and also some gases under pressure, vary in temperature in almost direct proportion to their pressure. It is also known that as these liquefied gases, or gases, are allowed to escape from their containers their temperature drops so rapidly that a portion of the gases frequently freezes in the containers and forms snow. For instance, in containers placed within fire extinguisher casings to discharge extinguishing compounds therefrom it is found that not only does the last portion of the CO₂ freeze therein but also that a diminution in pressure is noticeable as the gas escapes. Consequently a maximum of efficiency is not obtained from the liquefied gas by which the compound is to be discharged; and again if the container valve is left open after the container has been supposedly emptied and when the latter is housed in an extinguisher casing a pressure of gas is gradually built up within the latter by melting of the frozen portion of the gas which sometimes results in an explosion.

This invention aims to provide means for maintaining a substantially uniform temperature in containers as the liquefied gas, or gas, under pressure is allowed to escape therefrom, thereby preventing any marked drop in pressure, and also for providing means for utilizing all the gas in the container by elimination of the freezing of the last portion of the gas that now occurs. Thus, incidentally, the possibility of the gradual subsequent discharge of gas from the container above deferred to is also eliminated.

Another object of the invention is to provide means for accomplishing the purpose above set forth wherein material is inserted in the containers which has both rapid heat transmitting property and also a relatively high specific heat, so that heat is given off by it rapidly enough to offset the temperature drop in the containers that would otherwise occur as the gas escapes therefrom and during which period there is a tendency for the pressure of the gas therein to drop. Moreover the heat absorbing volume and radiating area of the material must, of course, be correctly proportioned to obtain the desired result.

With these and other objects and advantages in view which will become apparent as the specifi-

cation proceeds, the invention is hereinafter more fully described with the aid of the accompanying drawing, in which:

Figure 1 illustrates a sectional elevation of a gas container with my temperature equalizing means therein, and.

Figure 2 is a section on the line 2—2 of Figure 1.

Referring to the drawing, 1 designates a conventional vessel or container intended to hold gas or liquefied gas under pressure. Its neck 2 is internally threaded to receive a suitable valve 3 which, in the present instance, has a rotatable stem 4 the lower extremity of which rests in a slot formed transversely of the upper end of a threaded plug 5. The lower extremity of the latter normally rests on an annular seat 6 and prevents the passage of gas from the container 1 through the valve aperture 7 to the outlet 8. The plug 5 is in threaded engagement with the body of the valve 3 so that as the stem 4 is turned the said plug is rotated and consequently rises from its seat 6 to permit the passage of gas from the container through the valve outlet 8.

Within the container 1 I provide a plurality of bars or otherwise suitably shaped pieces of material 9. These are usually placed loosely within the container and are preferably so shaped that when resting against one another their total heat radiating area is not materially reduced. Therefore when using bars I prefer that they be of circular section.

These bars or pieces of material 9 may be of any desired material having a sufficiently high specific heat and coefficient of heat transmission to radiate heat quickly enough to compensate for the loss in temperature that would otherwise occur within the container 1 when the valve 3 is opened and the gas commences to escape.

I find that very good results may be obtained with aluminum on account of the degree to which the above properties are possessed by this metal; and when CO₂ is the liquefied gas it is in no way affected by the aluminum. Moreover the lightness of this metal is another favorable feature since the amount of material then necessary does not materially increase the weight of the container 1. Various copper alloys, and plain copper, may also be satisfactorily employed for my purpose.

Again whatever the cross sectional form of the material 9 care must be taken to provide both sufficient heat absorbing volume and heat radiating surface to compensate for the total amount of heat loss that would otherwise be sustained during the whole period of the gas discharge

from the container and at substantially the speed at which that loss would occur.

While in the foregoing the preferred form of my invention and method of utilizing it has been described and shown, it is understood that I may depart in detail therefrom so long as the embodiment falls within the scope of the appended claims.

What I claim as my invention and desire to 10 secure by Letters Patent is:

1. Means for substantially equalizing the temperature of volatile fluid under pressure within a container during its discharge from the latter consisting in the provision of material having a 15 relatively high coefficient of heat transmission placed within said container, said material having sufficient mass to absorb enough heat to offset the drop in temperature that would otherwise occur in the fluid remaining in the container as some 20 gasified fluid escapes therefrom, and said material having sufficient heat radiating area to give off its heat quickly enough to prevent any marked drop in temperature of the remaining fluid that would result in a marked drop in the pressure 25 of the remaining fluid.

2. Means for substantially equalizing the temperature of a volatile fluid under pressure within a container during its discharge from the latter consisting in the provision of material of relatively high specific heat placed within said container, said material having sufficient mass to absorb enough heat to offset the drop in temperature of the remaining fluid that would otherwise occur in the container as some of the gasified 30 fluid escapes therefrom, and said material having sufficient heat radiating surface to give off heat quickly enough to prevent any marked drop in temperature occurring that would result in a marked drop in the pressure of the remaining 35 fluid.

3. Means for substantially equalizing the temperature of liquefied gas under pressure within a container during its discharge from the latter consisting in the provision of a plurality of pieces 45 of material within said container, said pieces having enough mass and a sufficiently high specific heat to absorb enough heat to offset any material drop in temperature of the remaining gas that would otherwise result as some gas escapes 50 from the container, and said pieces having

enough radiating surface and a sufficiently high coefficient of heat transmission to radiate heat substantially as quickly as the temperature of the remaining gas would otherwise drop as gas escapes from the container.

4. Means for substantially equalizing the temperature of liquefied gas under pressure within a container consisting in the provision of pieces of aluminum within the container having sufficient heat absorbing mass and heat radiating surface to store enough heat and give it off rapidly enough to compensate for the drop in temperature of the remaining gas that would otherwise occur as some gas escapes from the container.

5. Means for substantially equalizing the temperature and pressure of liquefied CO₂ under pressure within a container during its discharge therefrom consisting of pieces of material of relatively high specific heat and a relatively high coefficient of heat transmission placed within the container.

6. Means for substantially equalizing the temperature and pressure of liquefied CO₂ under pressure within a container during its discharge 100 therefrom consisting of bars of aluminum placed within the container.

7. In a device of the class described, a container adapted to hold fluids under pressure, and a mass of material of a high heat absorbent and radiating character within the container, whereby the temperature of the fluid will remain substantially uniform during its discharge from the container.

8. In a device of the class described, a container adapted to hold fluids under pressure, and a mass of metallic material of a relatively high heat absorbent and radiating character within the container, whereby the temperature of the fluid will remain substantially uniform during its discharge 110 from the container.

9. In a device of the class described, a container, a volatile fluid within said container, and a mass of material of a high heat absorbent and radiating character within the container, whereby the temperature of the fluid will remain 120 substantially uniform during its discharge from the container.
